UNITED STATES PATENT OFFICE.

JOHN MCLEAN, OF LIME, OREGON.

FUSE CUTTING, SPLITTING, AND CAPPING MACHINE.

Application filed April 4, 1927, Serial No. 120,906, and in Canada January 17, 1927.

This invention relates to means for cutting, splitting and capping fuses such as used in blasting operations to ignite an explosive charge. Such fuses are formed of considerable length and require to be cut into short pieces of various lengths, to have one end of each piece partly split longitudinally and to have a cap or ferrule crimped on the other end. This has usually been effected by the use of a jackknife and a pair of crimping pliers, which is a slow and expensive method. My object, therefore, is to devise a machine which will measure lengths of fuse, and at one operation cut-off, split 10 and crimp a cap on each piece measured.

I attain my object by means of a construction which may be briefly described as follows: On a table, near one end, is supported a fuse reel, and at the opposite end a guide spool adjustable to and from the fuse reel. Intermediate the two ends, one towards the back and the other towards the front of the machine, are supported two sets of dies, one adapted to cut off and split one end of the 25 fuse; the other to crimp on its opposite end a cap which has been positioned by hand. The movable dies of the two sets are connected for simultaneous operation by a pedal.

The invention is hereinafter more fully described and is illustrated in the accompanying drawings in which

Fig. 1 is an end elevation, partly broken away, of the apparatus;

Fig. 2 a plan view of the same;

Fig. 3 a side elevation of the upper parts thereof;

Fig. 4 a plan view of the lower cutting and splitting die;

Fig. 5 a side elevation of the movable cutting and splitting dies;

Fig. 6 a front elevation of the crimping dies;

Fig. 7 a side elevation of the same; and

Fig. 8 a perspective view of a piece of 45 capped and split fuse.

In the drawings like numerals of reference indicate corresponding parts in the different figures.

1 is the frame of the machine, on which 50 is supported a table 2. On one end of the table is vertically journalled a fuse reel 3, which is adapted to receive and rotatably support a coil of fuse material. At the opposite end of the table is journalled a guide spool 4. This guide spool is adjustable towards and away from the fuse reel. For this

purpose I form a series of holes 5 in the table, into one of which may be inserted the lower end of a bolt 6, which forms the journal for the spool. A nut 7, threaded on the lower end 60 of the bolt, provides means for securing it in position.

Intermediate the fuse reel and guide spool are located the dies, preferably closer to the fuse reel than to the guide spool, as the position of the guide spool relative to the dies determines the length of the formed fuses. Towards one side of the machine are located the cutting and splitting dies 8 and 9, and opposite them, towards the other side of the machine, crimping dies 10 and 11. The stationary dies are secured to the table 2, while the movable dies are secured to the cross head 12, which is formed on or secured to the upper end of the rod 13 vertically movable 70 in a guide 14 secured to the table. A collar 15 adjustable on the guide rod, by means of a set screw 16, serves to limit the downward movement of the rod 13 and thus determines the co-operating position of the 80 dies. The rod 13 has its lower end threaded into a clevis 17, which is pivotally connected with a pedal 18 fulcrumed on a bearing 19. A coil spring 20 secured to the end of the pedal behind the fulcrum and to the frame 85 of the machine tends to maintain the pedal raised and the dies in spaced position.

The stationary cutting and splitting die 8 has a hole 21 formed therein having a flared mouth to facilitate the introduction of 90 the fuse material therein. Intersecting this hole are the transverse slot 22 and the longitudinal slot 23, the transverse slot extending down below the hole. The movable die 9 is formed with a transverse cutting blade 95 24 on the back of which is formed or secured a longitudinal blade 25, the cutting edge of which is above the cutting edge of the transverse blade. Thus, when the blades pass down in the slots, the fuse material will be 100 completely severed by the transverse blade when the longitudinal blade has reached a position adapted to split the end of the cut off length of fuse substantially to its centre. The stationary and moving crimping dies are of substantially the same form at their adjacent co-operating surface, each having a one-half round notch 26 formed therein of less diameter than the width of the die and of somewhat less diameter than that 105 of a cap 28. A stop 27 is secured to one of the crimping dies, preferably the lower, and

is positioned so that when the side of the cap is pressed against it the body of the cap is in proper position for the operation thereon of the dies.

5. The operation of the dies is as follows: The end of the fuse material is led from the reel 3 through the hole 21 in the lower cutting and splitting die, passed round the guide spool 4 and led to the crimping dies.
10. A cap is slipped over the end of the length of fuse and the cap positioned between the crimping dies. The pedal 18 is then depressed, causing a simultaneous operation of both sets of dies. The cutting and splitting 15 dies cut off a length of fuse and split the end adjacent the cut. The crimping dies crimp the cap on the other end of the fuse, as shown in Fig. 8. The length of the fuse, it will be seen, has been determined by the 20 position of the guide spool. Another length of the fuse material is then drawn from the cutting and splitting device round the guide spool to the crimping dies and the operation of cutting, splitting and crimping repeated.
25. What I claim is:
1. A fuse preparing machine comprising a table; fuse cutting and splitting means supported thereon; cap crimping means supported thereon; a guide spool round which the fuse material may be led from the cutting and splitting means to the cap crimping means; and means for simultaneously actuating the cutting and splitting and the cap crimping means.
  35. 2. A fuse preparing machine comprising a table; fuse cutting and splitting means supported thereon; cap crimping means supported thereon; a guide spool round which the fuse material may be led from the cutting and splitting means to the cap crimping means, said guide being adjustable to and from the aforesaid means to vary the length of fuse cut; and means for simultaneously actuating the cutting and splitting and the cap crimping means.
  40. 3. A fuse preparing machine comprising a table; a fuse reel supported on the table near one end; a guide spool supported adjacent the other end of the table; a set of dies adapted to cut and split a fuse and comprising a stationary and a movable die; a set of dies adapted to crimp a cap on a fuse also comprising a stationary and a movable die, both sets of dies being located intermediate the reel and guide spool and adjacent one another; a cross head to which the movable dies are secured; and a rod slidable on the apparatus to which rod the cross head is secured.
  45. 4. In a fuse preparing machine means for cutting and splitting fuses comprising a stationary die having a hole therein for the

passage of fuse material and slots intersecting said hole both longitudinally and transversely; and a movable die provided with 65 knife blades adapted to enter said slots, the knife entering the transverse slot having its cutting edge leading the cutting edge of the knife blade entering the longitudinal slot, whereby the fuse is cut off when the latter 70 cutting edge has passed only part way through the fuse.

5. In a fuse preparing machine means for cutting and splitting fuses comprising a stationary die having a hole therein for the 75 passage of fuse material and slots intersecting said hole both longitudinally and transversely; and a movable die provided with a transverse knife blade and a longitudinal knife blade at the back of the transverse blade having its cutting edge above the edge of the said transverse blade, whereby the fuse is cut off when the latter cutting edge has 80 passed only part way through the fuse.

6. In a fuse preparing machine means for crimping a cap or ferrule on the fuse comprising a stationary die and a movable die, each having a half round notch formed in its working surface of a diameter less than the width of such surface and somewhat less 90 than the diameter of the cap; and a cap stop secured to one of the dies adapted to position the cap for engagement by the dies.

7. A fuse preparing machine comprising a 95 table; fuse cutting and splitting means supported thereon; cap crimping means supported thereon; and means for simultaneously actuating the cutting and splitting and the cap crimping means.

8. A fuse preparing machine comprising a 100 table; a set of dies adapted to cut and split a fuse and comprising a stationary and a movable die; a set of dies adapted to crimp a cap on a fuse also comprising a stationary and a movable die; a cross head to which the movable dies are secured; and a rod slidable on the apparatus to which rod the cross head is secured.

9. A fuse preparing machine comprising a 110 table; fuse cutting means supported thereon; cap crimping means supported thereon; means for simultaneously actuating the cutting and the cap crimping means; and a guide round which fuse material may be 115 led, positioned so that while one end of the fuse material is being capped the cutting means is severing the fuse material to form a fuse of a length determined by the position of said guide means relative to the cutting and cap crimping means.

Signed at Lime, Oregon, this 21st day of March, 1927.

JOHN McLEAN.
